UNITED STATES PATENT OFFICE.

FRANK W. BEBERDICK, OF WEST HOBOKEN, NEW JERSEY.

DESIGN FOR A VEST-PATTERN.

SPECIFICATION forming part of Design No. 30,298, dated February 28, 1899.

Application filed February 3, 1899. Serial No. 704,431. Term of patent 14 years.

To all whom it may concern:

Be it known that I, FRANK W. BEBERDICK, a citizen of the United States, residing at West Hoboken, in the county of Hudson and State 5 of New Jersey, have invented and produced a new and original Design for a Vest-Pattern, of which the following is a specification, reference being had to the accompanying drawing, forming part thereof.

10 The drawing represents in plan view a pattern of one side and half of the back of the vest, showing my new design, and it will be understood that the other side and half of the back are the same.

15 As shown in the drawing, the leading or material feature of my design consists in the part A, forming one side and half the front, and the part B, forming half of the back, and in the particular shape or contour given to 20 the upper edge or ends of these parts. From the point a the front edge of the part A extends upwardly and inwardly in a curved line a' to the point a^2 , from whence the edge extends in a slight downward and then upward 25 curve to the point a^3 , forming the compound-curved line a^4 , which represents the shoulder-seam of the garment. The point a^3 is located below the point a^2 . The lines a^4 and a' , being 30 similarly curved adjacent to their meeting-point a^2 , form a sharp upwardly-projecting point. The edge of the upper portion of the part A extends downwardly and inwardly from the point a^3 in a curved line deviating only slightly from a straight line to the point 35 C^2 , from which point the said edge extends in a full curve to the point a^5 . From the point a^5 the edge extends downwardly in a slightly-curved line to the point a^6 , which point is located in substantially the same vertical plane as the point a^3 . From the point a^6 40 the edge extends in a slightly-curved line which is downwardly inclined to the point a^7 , from which point the edge extends upwardly in an outwardly-inclined straight line to the point a . The point a is on substantially the

same horizontal plane as the point a^5 , while the point a^2 is located substantially midway between the vertical planes passing through the points a^5 and a .

The outer edge of the part B extends in a 50 substantially straight line from the point b to the point b' , from which it extends in a slightly-curved line which is downwardly inclined to the point b^2 . From the point b^2 the edge extends upwardly in a curved line to 55 the point b^3 , which point is on the same horizontal plane as the point a^5 of the part A, while the point b^2 is slightly below the horizontal plane of the point a^6 . From the point b^3 the edge of the part B extends upwardly 60 and inwardly in a curved line to the point C^3 , from whence the said edge extends upwardly 65 in a slightly-inclined curved line, which deviates only slightly from a straight line, to the point b^4 . The point b^4 is located slightly below the horizontal plane of the point a^3 of the part A and is separated therefrom, forming the space b^6 . From the point b^4 the edge 70 of the part B extends upwardly in a sharply-inclined line, which is slightly curved at its upper portion, to the point b^5 . The upper edge of the part B extends from the point b^5 in a downward curve to the point b , which point is located slightly below the point b^5 , but above the horizontal plane passing through 75 the point a^3 of the part A.

Having fully described my invention, I claim as new and desire to secure by Letters Patent—

The design for a vest-pattern substantially 80 as herein shown and described.

In testimony that I claim the foregoing as my invention I have signed my name, in presence of the subscribing witnesses, this 21st day of January, 1899.

FRANK W. BEBERDICK.
